CLAIM

The ornamental design for a heat transfer disc for cooking, as shown and described.

DESCRIPTION

FIG. 1 illustrates a perspective view of a heat transfer disc for cooking;

FIG. 2 illustrates a top plan view thereof;

FIG. 3 illustrates a bottom plan view thereof;

FIG. 4 illustrates a right side elevational view thereof;

FIG. 5 illustrates a left side elevational view thereof;

FIG. 6 illustrates a front side elevational view thereof; and,

FIG. 7 illustrates a rear side elevational view thereof.
